UNITED STATES PATENT OFFICE.

LOUIS T. WEISS, OF NEW YORK, N. Y., ASSIGNOR TO RELIANCE-GRANT ELEVATOR EQUIPMENT CORPORATION, OF NEW YORK, N. Y.

DOOR-HANGER.

1,325,428.

Specification of Letters Patent. Patented Dec. 16, 1919.

Application filed January 25, 1919. Serial No. 273,119.

To all whom it may concern:

Be it known that I, LOUIS T. WEISS, a citizen of the United States, residing at New York, in the county of New York and 5 State of New York, have invented new and useful Improvements in Door-Hangers, of which the following is a specification.

This invention relates to means for hanging laterally movable doors and other closures, and particularly to hangers of that type embodying relatively sliding members, one serving as a stationary track and the other as a sliding support movable in or upon said track and from which the door 15 is hung, combined with antifriction bearings interposed between said members to secure a free and easy relatively sliding motion thereof.

One object of the present invention is to 20 provide a novel and improved type of ball spacer for a hanger of the class described, with means for retaining said spacer in working position and preventing its disengagement or displacement.

Another object of the present invention 25 is to provide simple, reliable and efficient means, coöperating with the ball spacer and the bearing balls, to center the sliding member and maintain it in proper relative position with respect to the stationary member, thus preventing relative tilting or canting 30 of the parts or binding of the balls and securing a desirable and efficient antifriction bearing action.

The invention consists of the features of 35 construction, combination and arrangement of parts hereinafter fully described and claimed, reference being had to the accompanying drawing, in which:—

40 Figure 1 is a fragmentary sectional perspective view of a door hanger embodying my invention, with a portion of the hanger bar broken away to show the interior construction.

45 Fig. 2 is a vertical transverse section through the hanger, showing a slightly different arrangement of the ball carrier.

Fig. 3 is a perspective view of one form 50 of the ball spacer employed.

Fig. 4 is a top plan view of the hanger bar showing one arrangement of centering devices which may be used.

Fig. 5 is a similar view of the hanger bar showing an instance of another arrange-

ment of centering devices which may be used.

Fig. 6 is a perspective view of a ball spacer with a modified form of guiding or retaining means.

In the practical embodiment of my invention as disclosed herein, I provide a door hanger consisting of relatively sliding members 1 and 2, the member 1 consisting of a hollow sheet metal body and the member 2 a bar or rail slidably fitted therein. The 60 member 1 forms a hollow stationary track for the inclosed sliding bar 2, and is designed in practice to be fastened in the desired supporting position in any preferred manner, while the member 2 forms a support 65 for the door and from which the door is hung for sliding opening and closing motions.

The hollow track member 1 is formed of a continuous side wall 3, a top wall 4, a 75 short opposite side wall 5, and a bottom wall or flange 6, the latter extending horizontally from the lower edge of the wall 3. The wall 5 is of comparatively short depth, terminating a short distance below the top 80 or crown wall 4, whereby a slot or opening 7 is formed between the same and the bottom wall 6 through which one side of the sliding bar is exposed for the attachment thereto of the brackets or fastening means 85 employed for hanging the door therefrom.

The sliding bar 2 is of materially less depth than the interior of the hollow track member 1, and said bar has a sliding and antifriction bearing engagement at its 90 lower edge with the bottom wall 6 of the track member. As shown in the present instance the bar is provided in its lower face with a longitudinal groove or raceway 8, while the wall 6 is stamped up or offset to 95 provide a coöperating ball groove or raceway 9, a row or series of antifriction bearing balls 10 being provided for engagement with said raceways, thus forming an antifriction bearing support for the hanger bar. 100

The antifriction balls 10 are arranged at suitable intervals apart and are fitted within retaining openings 11 in a ball spacer 12. This ball spacer 12 consists of a metal plate disposed horizontally and longitudinally between the bearing surfaces of the track and bar and mounted for a predetermined sliding movement in any preferred manner with 105

the bar 2 in its opposite travels, thus allowing the bar to have free and easy backward and forward movements with a minimum degree of friction and resistance at the 5 points where the greatest pressures and strains come upon the parts of the hanger from the weight of the suspended door. The retaining openings 11 are of a diameter slightly larger than the diameter of the balls 10 to permit the balls to turn freely therein, and to roll in contact with the surfaces of the raceways, while retaining the balls in position against any possibility of displacement. The arrangement may be such that 15 the ball spacer plate 12 may slide in frictional contact with the surfaces 13 and 14 of the wall 6 at opposite sides of the raceway 9, as shown in Fig. 1, or said spacer plate may be disposed so as to be elevated 20 slightly above said surfaces and normally travel out of contact therewith, as illustrated in Fig. 2.

For the purpose of retaining the spacer plate 12 in proper working position and 25 holding it from upward movement or displacement under shocks or jars falling upon the door structure, means of a novel character is provided for engagement with an external portion of the track member 1 for 30 maintaining the plate in working position while permitting it to slide freely in its movements. This means consists of one or more retaining flanges or members projecting outwardly from the relatively outer edge 35 of the spacer plate through the slot or opening 9 and arranged to bear against the underside of the track 6 whereby upward movement of the spacer plate will be prevented. In the form of retaining means 40 shown in Figs. 1 and 2 for the purpose described, the retainer consists of a flange formed of a plurality of separated portions 45 arranged at proper intervals and extending downwardly at an angle from the outer edge of the plate and thence bent under the wall 6 to provide portions 16 engaging said wall to hold the plate from upward movement and maintain its normal disposition 50 and path of travel. In Fig. 6 the retaining flange 15' is shown as extending continuously along the outer edge of the ball spacer plate and having a portion 16', which 55 may be continuous or otherwise, to serve the same function as the portion 16. It is, therefore, to be understood that the angular retaining flange, constructed and arranged as described, may be either continuous, or formed of a single element, or of an interrupted character, that is, formed of a series 60 of separated portions, and that these and other equivalent constructions for the purpose are held to fall within the terms "retaining means" or "retaining flange," as set forth in the claims, except where a particular construction is specifically defined.

The upper edge of the bar 2 may terminate below the top wall 4 of the hollow track member 1, substantially coincident with the horizontal plane of the lower edge of the short wall 5, and suitable means may be 70 provided upon the bar and within the superposed head portion of the hollow track member for centering the bar and holding it from tilting or canting. To this end, the bar 2 may be provided at or adjacent to its 75 ends, or at suitably separated points, with horizontally disposed revoluble centering members 17, mounted to revolve upon vertical axes 18, and having rounded peripheries projecting equally beyond opposite sides of 80 the door to engage and travel as well as revolve in grooves or raceways 19 formed in the opposed portions of the walls 3 and 5 of the hollow track member 1. These revoluble disks will hold the upper portion 85 of the bar steady and from tilting motion in any direction, and will coöperate with the antifriction bearing construction between the bottom portions of the bar and hollow track to prevent displacement of the bar 90 from its normal working position. It will, of course, be understood that the revoluble disks will also serve as stops to prevent the bar 2 from jumping under shocks or jars 95 out of engagement with the antifriction bearing balls. The arrangement of the revoluble retaining members may be varied in many respects, one instance of which is shown in Fig. 5, wherein the outer disks 17^a are illustrated projecting peripherally 100 beyond one side of the bar only for engagement with the groove in one side of the track and an intermediate disk 17^b is employed and projects beyond the opposite side of the bar for engagement with the groove in the 105 opposite side wall of the track, the dotted lines in Fig. 6 showing equalizing lines of strain passing through the axes of the disks, relative to the longitudinal center line of the bar, whereby the strains are equally distributed 110 and the bar steadily maintained in a normally vertical position.

It will be seen that by the constructions described simple and effective means for retaining the ball spacer in proper working 115 position and for holding the bar against displacement are disclosed, and a type of hanger produced which is free from a complication of parts and may be economically manufactured. It is to be understood, of 120 course, that while the hanger member 1 is described as the fixed member and the member 2 the sliding door supporting member, this condition may be reversed without departing from the spirit and scope of the invention, that is to say, that the door may be suspended from the member 1 which will travel upon the member 2, which in this case will be fixedly secured in the desired 125 position.

Having thus fully described my invention, I claim:—

1. In a door hanger, relatively fixed and sliding members, one inclosing the other, the 5 inclosing member having a slot in a wall thereof, antifriction bearing balls between opposed surfaces of said members, a spacer disposed between said opposed surfaces and having openings through which the balls 10 project, and a retaining means upon said spacer extending through said slot and engaging an external surface of the inclosing member to hold said spacer against displacement.
- 15 2. In a door hanger, a hollow track member having a side opening and a bottom wall provided with a raceway, a bar slidable in said hollow track member and having a co-operating raceway in its lower face, anti-friction balls disposed in said raceways, a ball spacer plate disposed between the bearing surfaces of the track and bar and provided with openings through which the balls 20 project, and a retaining means upon the 25 plate projecting beneath the bottom wall of the hollow track member and holding said spacer plate against upward displacement.
- 30 3. In a door hanger, a hollow track member having a side opening and a bottom wall, the latter provided with a raceway, a bar slidably mounted in the hollow track member and having a co-operating raceway in its lower face, antifriction bearing balls 35 engaging said raceways, a ball spacer plate disposed between the bearing surfaces of the hollow track member and bar and having openings through which the balls extend, and projecting means upon one longitudinal 40 edge of said spacer plate extending outwardly through said side opening and engaging beneath the bottom wall of the hollow track member to hold said ball carrier plate from upward displacement.
4. In a door hanger, a hollow track member having a side opening and a bottom wall, the latter provided with a raceway, a bar slidable in the hollow track member and having its lower surface provided with a co-operating raceway, antifriction balls 45 engaging said raceways, a ball spacer plate disposed between the bearing surfaces of the hollow track member and bar and having openings receiving the balls and through which said balls extend, and a retaining 50 flange upon the outer edge of said plate projecting externally through the side opening in the hollow track member and beneath the bottom wall thereof and engaging said bottom wall to hold the spacer 55 plate from upward displacement.
5. In a door hanger, the combination of a hollow track member having opposed side walls, a top wall and a bottom wall, one of said side walls having its lower portion cut 60 away to form a slot, the upper portions of the side walls being provided with longitudinal grooves and the bottom wall also being provided with a longitudinal groove, a bar slidable in the hollow track member 65 and having its lower surface provided with a groove for co-operation with the groove in the bottom wall of the hollow track member, antifriction bearing balls engaging said co-operating grooves, a retainer having openings receiving the balls and provided with means projecting through the slot in the hollow track member and engaging the underside of the bottom wall to hold said retainer from upward displacement, and disks 70 revolvably mounted upon the upper edge of the bar and having peripheral portions engaging the grooves in the upper portions of the side walls of the hollow track member.

In testimony whereof I affix my signature

LOUIS T. WEISS.
